US00D975633S

(12) **United States Design Patent** (10) **Patent No.:** **US D975,633 S**
Chen (45) **Date of Patent:** **** Jan. 17, 2023**

(54) **RECHARGEABLE BATTERY**

(71) Applicant: **Huiyu Chen**, Guangdong (CN)

(72) Inventor: **Huiyu Chen**, Guangdong (CN)

(**) Term: **15 Years**

(21) Appl. No.: **29/772,424**

(22) Filed: **Mar. 1, 2021**

(51) **LOC (14) Cl.** **13-03**

(52) **U.S. Cl.**

USPC **D13/103**

(58) **Field of Classification Search**

(57) **CLAIM**

The ornamental design for a rechargeable battery, as shown.

DESCRIPTION

FIG. 1 is a front elevational view of a rechargeable battery showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is second perspective view thereof;

FIG. 9 is third perspective view thereof; and,

FIG. 10 is fourth perspective view thereof.
